UNITED STATES PATENT OFFICE.

HARRY W. ELLIOTT, OF PRESCOTT, ARIZONA TERRITORY.

LUBRICATING SYSTEM.

No. 818,364.

Specification of Letters Patent.

Patented April 17, 1906.

Application filed December 21, 1905. Serial No. 292,697.

To all whom it may concern:

Be it known that I, HARRY W. ELLIOTT, a citizen of the United States, residing at Prescott, in the county of Yavapai and Territory of Arizona, have invented certain new and useful Improvements in Lubricating Systems, of which the following is a full, clear, and exact description.

My invention relates to a system for minimizing the excessive friction which is incident to vehicles rounding a curve upon a track. The usual method of accomplishing this is by manually greasing the sides of the rails at the curves thereof, so that when the flanged wheels of the vehicle traverse the same the heavy lateral forces of the flanges against the rails will be borne by the lubricated surfaces. As is well known this greatly reduces the noise, vibration, and power required, and it further decreases the liability of the flanges climbing the rails, which is a common cause of derailments.

The principal object of my invention is to provide a system in which the flanges of the wheels instead of the rails are lubricated and by a means within the vehicle and under the control of the engine man or operator.

A further object of the invention is to provide means by which ordinary crude petroleum may be applied in a smooth even zone upon the required wheel-flanges, so as to fully lubricate the same and at the same time be absolutely prevented from getting on the tread of the wheels.

With these and other objects in view my invention consists in the construction, combination, location, and arrangement of parts, all as will be more fully hereinafter described, as shown in the accompanying drawings, and 40 finally particularly pointed out in the appended claims.

In the drawings, Figure 1 is a diagrammatic view illustrating a locomotive equipped with a flange-lubricating system embodying the principles of my invention. Fig. 2 is a detail view showing the relation of the oil-nozzles to the wheel-flanges.

In carrying out my invention I make use of a current of steam under comparatively low pressure and temperature as a conveyer for the oil, and I introduce crude petroleum into this current of steam, which is carried along with it and delivered at suitable issuing nozzles. By employing a current of steam under low pressure and temperature conditions I avoid unduly heating the oil, which

would evaporate its inflammable constituents and be otherwise objectionable and dangerous.

Referring now to the drawings and to the various views and reference-signs appearing thereon, in which like parts are designated by the same reference-sign wherever they occur, 1 indicates the locomotive, having driving-wheels 2 and having within the cab thereof a receptacle or feeder 3 for crude petroleum or lubricating-oil of any sort, such as that of my companion application, Serial No. 292,698, filed herewith.

4 indicates a steam-turret for obtaining a supply of steam under reduced pressure and temperature conditions. I conveniently attain the required pressure and temperature by interposing a choke-valve 5 within the steam-passage from the steam-turret 4. 70 While I have illustrated my system applied to a locomotive and utilizing my oil-feeder as above stated, I do not desire to be limited or restricted to this use, since it is evident that the system is applicable to any style of vehicle which runs upon track-rails and may employ any form of oil-feeder.

From the source of reduced steam-pressure 5 and the oil-feeder 3 I lead a pipe 6 of suitable diameter and material to convey the steam and oil and which divides into branches 7 and 8, leading to the respective wheels. 9 9' designate cocks within the several branches for controlling the flow therein. The branch pipe 7 is led forwardly either within or outside of the usual boiler-jacket and terminates in additional branches 10 and 11, also containing cocks 12 and 12', similar to the cocks 9 and 9', previously referred to. 14 designates an ordinary steam-hose, forming part of the branch pipe 10, which permits a certain amount of flexibility therein.

All of the branch pipes 8, 10, and 11 terminate in reduced extremities 15 in proximity to the wheel-flanges, as clearly indicated in Fig. 2. In the practical carrying out of my invention I form the extremities 15 integral with the main body of the pipe and turned laterally toward the wheel-flanges and having apertures or nozzles therein of three thirty-seconds of an inch in diameter or thereabout. These are located about one inch from the flange, so that a conical spray is delivered against the wheel-flanges covering an annular zone about an inch in width upon the surface of the flange.

The entire system may be duplicated for

the wheels upon the opposite side of the vehicle, and by manipulating the various cocks 9 9' and 12 12' the oil may be applied to flanges of any particular wheels on either or 5 both sides of the vehicle. When the vehicle is not traversing a curve, the entire supply may be cut off by manipulating the usual valves of the oil feeder or receptacle 3.

It will be seen that in the operation of the 10 above lubricating system the oil is applied exclusively upon the interior surfaces of the wheel-flanges and in no case upon the tread of the wheel. No matter how thickly the oil is applied to the flanges it cannot run or creep 15 or get upon the tread of the wheels in any way, since the centrifugal force due to the rotation impels all superfluous oil outward and away from the tread of the wheel. I regard this as an important feature of the invention, 20 since it is always essential to keep the tread of the wheels dry and free from oil in order to secure proper traction.

What I claim is—

1. A system of lubricating the frictionally- 25 engaging surfaces of a track and vehicle-wheel comprising a pipe adapted to deliver a current of steam and atomized oil against one of such surfaces.
2. A system of lubricating the frictionally- 30 engaging surfaces of a flanged wheel and track-rail comprising a pipe extending into proximity to the wheel-flange, and adapted to deliver a current of atomized oil thereagainst.

3. A system of lubricating the frictionally- 35 engaging surfaces of a flanged wheel and track-rail comprising a pipe having a nozzle in proximity to the wheel-flange, and connected to an oil-supply and a source of steam-pressure.

4. A system of lubricating a wheel-flange comprising an oil feeder or receptacle, and a pipe in communication with said receptacle and with a source of steam under reduced pressure and temperature conditions, said 45 pipe terminating in an orifice in proximity to the wheel-flange.

5. A system of lubricating a wheel-flange comprising an oil-receptacle, and a source of fluid-pressure, and means for delivering oil 50 particles in a current of the fluid against the wheel-flange.

6. A system of lubricating a wheel-flange comprising a steam-pipe having a nozzle in proximity thereto, and means for introducing crude petroleum into the steam-pipe.

7. A system of lubricating the wheel-flanges of a vehicle comprising a source of steam-pressure, and an oil-receptacle, and pipes having nozzles for delivering a current 60 of steam carrying oil particles against the surface of the flanges.

In witness whereof I subscribe my signature in the presence of two witnesses.

HARRY W. ELLIOTT.
